UNITED STATES PATENT OFFICE.

OCTAVIUS HENRY ST. GEORGE ANSON, OF MADISON, WISCONSIN.

PERPETUAL CALENDAR.

SPECIFICATION forming part of Letters Patent No. 604,649, dated May 24, 1898.

Application filed May 25, 1897. Serial No. 638,051. (No model.)

To all whom it may concern:

Be it known that I, OCTAVIUS HENRY ST. GEORGE ANSON, of Madison, in the county of Dane and State of Wisconsin, have invented certain new and useful Improvements in Perpetual Calendars; and I do hereby declare the following to be a full, clear, and exact description of the invention, such as will enable others skilled in the art to which it appertains to make and use the same.

My invention relates to improvements in calendars, and has for its object the production of a calendar of the perpetual type embodying the desirable advantages of cheapness and simplicity.

With this and other advantages in view the invention consists in the novel constructions and combinations hereinafter more fully described, and particularly pointed out in the appended claim.

In the accompanying drawings, illustrating the invention, Figure 1 is a perspective view of the calendar. Fig. 2 is a front elevation or face view of the same, showing the calendar-card removed; and Fig. 3 is a longitudinal sectional view on the line 3 3 of Fig. 2.

Referring now more particularly to the drawings, the numeral 1 designates the calendar-frame, which is open at the front, as shown, to expose the calendar face or card 2. This case is provided with a pivoted back 3, designed to serve as a rest for supporting the calendar in an upright position.

The calendar card or face 2 is provided with columns of numerals representing days of the month in groups of seven, except the last column, which has only three numerals, the numerals of the several columns ranging from "1" to "31," inclusive. The calendar-card is also provided at one side adjoining the first column of numerals with a longitudinal slot 4 to expose an endless roll 5, containing the names or abbreviations of the days of the week in their regular sequence or order. This roll is mounted upon shafts

5^a 6, having bearings in the end wall of the frame, and the latter is provided on the exterior with a knob 6^a, whereby it may be revolved to move the roller. The calendar face or card is also provided with slots 7 and 8 at the top thereof, the former being employed to expose a portion of a roll 9, which bears

the names or abbreviations of the months of the year. This roll is mounted upon shafts 10 11, the former being provided with a knob 55 10^a. The slot 8 is arranged at one side of the said slot 7 and is designed to expose a roll 12, bearing terminal numerals "97" to "15," representing the fractional year or portion of a century. This roll is mounted upon shafts 60 13 14, the former provided with a knob 14^a. The face of the calendar-card on the opposite side of the slot 7 from the said slot 8 bears the numeral "19," and arranged above it is a perforated slip 15, bearing the numeral 65 "18." These numerals "18" and "19" are designed to be read in connection with the numerals on the roll 12 to designate the year. Thus the slip 15, bearing the numeral "18," will be employed in connection with the numerals "97," "98," and "99" on the roll 12 70 until the year 1900, when the said slip will be detached to expose the numeral "19," which is adapted to be employed in connection with the numerals "00" up to "15" on 75 said roll. It will be understood, of course, that the roll may be provided with numerals adapted to extend through an indefinite period.

The columns of the numerals on the calendar face or card 2 range, as before stated, from "1" to "31," inclusive, which adapts it for use for indicating the days of the month, arranged in "28" the lowest or "31" the highest. I have provided a concealing-slide 17, 80 85 adapted to conceal one or all of the numerals in the last column, so that the calendar face or card may be made to expose only the number of days contained in the calendar month—that is, twenty-eight for February, thirty for 90 April, and thirty-one for May. This concealing-slide is constructed to correspond with the appearance of the face or calendar card and is connected with the shank of an actuating-slide 18, which projects through and operates 95 in a longitudinal slot 19 in the frame adjoining one side thereof.

My invention provides a simple and inexpensive construction of calendar which may be adapted for use for an indefinite period. 100 The desideratum in a calendar of this character is cheapness and simplicity, and this my invention embodies.

Having thus described my invention, what

I claim as new, and desire to secure by Letters Patent, is—

In a calendar of the character set forth, the combination of a rectangular frame open at the front and having a pivoted back to serve as a rest therefor, and also formed with a longitudinal slot in one of the frame sides, a calendar-card mounted in the said frame and divided into columns representing the days 10 of the month and also formed with a longitudinal slot as well as upper slots, an endless roll movable against the back of the frame containing days of the week and also an upper roll bearing the names of the months of the year, one of the slots at the top of the frame being adapted to expose a roll bearing terminal numerals representing the fraction of a year or portion of a century, and a concealing-slide movable over the card at one

side thereof to conceal one or all of the numerals in the last column of the same, and connected to cranks of an actuating-slide, the said cranks projecting through the slot in one side of the frame and the actuating-slide being of greater width than the said slot and 20 located on the exterior of the frame and provided with an operating-knob, the said shanks also providing stops to abut against the upper and lower terminations of the slot in the side of the frame and limit the movement of 25 the concealing-slide.

In testimony whereof I have signed this specification in the presence of two subscribing witnesses.

OCTAVIUS HENRY ST. GEORGE ANSON.
